UNITED STATES PATENT OFFICE.

JONATHAN P. SMYTHE, OF WASHINGTON, DISTRICT OF COLUMBIA.

WATER-JACKET FOR HEATERS.

1,163,787.

Specification of Letters Patent. Patented Dec. 14, 1915.

Application filed July 3, 1914. Serial No. 848,942.

To all whom it may concern:

Be it known that I, JONATHAN P. SMYTHE, a citizen of the United States, residing at Washington, in the District of Columbia, 5 have invented new and useful Improvements in Water-Jackets for Heaters, of which the following is a specification.

The invention relates to water heaters, and more particularly to the class of hot 10 water heaters or water jackets therefor.

The primary object of the invention is the provision of a jacket wherein cold water will be caused to circulate in columns therein so that these columns will be subjected to 15 the heat from the burner of the heater for preheating the water before consumption thereof through the spigot in the ordinary well-known manner, certain of the columns of water being disposed directly in the path 20 of the flames from the burner when lighted, thereby insuring the quick heating of the water on its admission to the water jacket with a resultant minimum use of fuel for this purpose.

Another object of the invention is the provision of a water jacket wherein the water circulating spaces are arranged in a 25 novel manner therein so that cold water will first flow in one direction in the jacket, and thence in a reverse direction within the said 30 jacket for the pre-heating of the water prior to consumption thereof, and in this manner the condensation of the atmospheric water on the inside of the jacket is eliminated, 35 and thereby avoids the formation of acid water with resultant corrosive action on the walls or metals within the casing.

A further object of the invention is the provision of a water jacket of this character 40 wherein the construction thereof is of novel form so as to direct the water entering the heater and divide it into inner and outer columns, the outer column of water serving to sustain the jacket cool at the outer 45 wall thereof, while the inner columns of water will be subjected to the heat from the burner or burners for the pre-heating thereof before circulating through the inner system, the inner columns of water being circulated in a manner to receive the full heating 50 effect from the burner or burners for the quick heating of the water prior to its leaving the heater.

A still further object of the invention is the provision of a water jacket of this character wherein the inner water courses there- 55 in cause the water to circulate in the direction of the path of the heat from the burner or burners so as to be constantly subjected thereto for the pre-heating of the water 60 through the water-ways in the casing.

A still further object of the invention is the provision of a water jacket of this character which is extremely simple in construction, thoroughly reliable and efficient in its 65 purpose, strong, durable, and inexpensive in manufacture.

With these and other objects in view, the invention consists in the construction, combination and arrangement of parts as will be 70 hereinafter fully described, illustrated in the accompanying drawings, and pointed out in the claims hereunto appended.

In the drawings: Figure 1 is a vertical longitudinal sectional view through a heater 75 constructed in accordance with the invention. Fig. 2 is a sectional view on the line 2—2 of Fig. 1. Fig. 3 is a sectional view on the line 3—3 of Fig. 1.

Similar reference characters indicate corresponding parts throughout the several views in the drawings.

Referring to the drawings in detail, the heater comprises a cylindrical casing 5 which may be of any desirable length, pref- 85 erably constructed from metal, and has fitted on its lower end a casting forming a water inlet ring 6 provided with an externally de- 90 pending annular flange 7 over which is tele- scoped a burner housing 8 supported upon legs 9, while fitted to the upper end of the casing 5 is a dome or crown 10 formed with a central chimney or flue nipple 11 provided with outlet apertures 12 circumferentially thereof. Within the dome or crown 10 and 95 spaced therefrom is a lining 13, the same being held in its spaced relation to the dome or crown through the medium of spacer disks 14 having passed therethrough rivets 15 which are also passed through the dome 100 or crown and lining for uniting the same together. The dome or crown 10 is mounted upon a top ring 16 which is fitted upon the upper end of the casing 5 and is fastened thereto in any suitable manner.

Arranged interiorly of the casing 5 is a

cylindrical inner wall or lining 17 forming a water jacket, which is spaced from the said casing to provide a water space 18 therebetween, the said lining 17 being extended 5 longitudinally within the casing throughout the length thereof so that the water space 18 will be coextensive with the casing. This lining 17 at its opposite end is connected with respective flanges 20 and 21 formed on 10 the top and bottom rings at the ends of the casing, the lining being bent at intervals throughout its length to form hollow annular ribs 22 which protrude inwardly in horizontal planes within the casing, while arranged within the water space 18 between the body 5 and the lining 17 are co-axially arranged spaced cylindrical partitions 23 and 24 respectively, the partition 23 at its lower end being fixed in the water inlet ring 6 to extend upwardly within the space 18 with its opposite upper end terminating spaced from the upper ring 16, while the partition 24 is fixed in the said upper ring 16 and extends downwardly through the 25 space 18 with its lower end terminating spaced from the lower ring 6, the free ends of the partitions being formed with reversely bent centering ears 25 at right angles thereto which are adapted to engage 30 the walls next thereto for positioning the partitions 23 and 24 in spaced relation to each other and also with respect to the casing 5 and lining 17 so as to form independent water passages therebetween. The ears 35 25 permit the passage of water from one independent course to the other within the casing of the heater.

Formed on the ring 6 is a water inlet nipple 26 so that water will be admitted to 40 the said ring at the outer side of the partition 23 and will rise in the space between the casing 5 and the outermost partition 23, then will flow over the upper free edge of the outer partition 23 downwardly through 45 the space between the said outer and inner partitions 23 and 24 and over the lower free edge of the partition 24, and thence upwardly between the latter and the lining 17 toward the upper end of the casing, whence the said water will circulate in a manner presently described.

Formed on the upper ring 16 are a series of radially arranged connecting tubes 27 which are disposed in the same plane with 55 each other and are directed toward the center of the said ring 16 and have down-turned nipples 28 at their inner ends, and to these ends is connected a hollow spider 29, to the outer ends of the radial arms of 60 which are fixed depending water circulating legs 30, while engaged in the nipples 28 are tubes 31, the latter being extended centrally through the legs 30 and have their lower ends terminating spaced from the

lowermost closed extremities of the said 65 legs so that water will be admitted from the upper ring 16 into the tubes 31 downwardly therethrough and into the legs 30, whence the water will flow upwardly without the said tubes 31 into the spider 29, the legs 30 70 each being formed at intervals with external hollow ribs 32 and a hollow terminal head 33, the latter being spaced from and in alignment with the burner 34, which may be of any approved form, and arranged within 75 the burner housing 8 of the casing so that the heat from the said burner 34 will play directly upon the legs 30 for the heating of the water circulating therethrough.

The spider 29 has centrally connected 80 thereto a thermostatic rod receiving tube 35 in which is adapted to be arranged a suitable valve operated thermostatic rod, (not shown), the tube 35 being extended downwardly and forming an outlet for the water 85 circulated within the casing and heated prior to its delivery to the house system. Arranged co-axially about the tube 35 which extends downwardly centrally within the casing to the lower end thereof is a spaced 90 tubular water leg 36 having a restricted lower end 37 embracing the tube 35 and closing the said lower end of the leg, while passed through the upper end of the said leg 36 and extended downwardly centrally 95 between the latter and the tube 35 is a tubular partition 38, the same at its upper end being connected to the said tube 35 within the spider 29, the connected end of the partition 38 being cut to form openings 39 establishing communication between the hollow 100 spider and the water circulating space 40 between the tube 35 and the partition 38, so that the water from the spider will flow downwardly in said space 40 and thence upwardly through the leg 36 in the space 41 between it and the partition 38, the tube 35 and partition 38 being fitted with nipples 42 for establishing communication between the leg 36 and the tube 35 at the upper end of 110 the said leg so that water flowing upwardly through the space 41 will pass through the nipples 42 through the tube 35, for its discharge to the house system, the discharge being automatically controlled through suitable valve mechanism acted upon the thermostatic rod arranged within the said tube 35, the upper end of the leg 36 being secured to the partition 38 directly above the nipples 42 in any suitable manner, while the partition 38 is passed through a stuffing box 43 formed centrally on the spider 29 and has its upper end suitably secured to the tube 35 so that the partition will depend centrally from 115 the said spider within the casing.

The center leg 36 is formed at intervals with hollow annular ribs 44. The ribs on all of the legs and the lining within the cas-

ing serve to increase the area of the heating surfaces thereof which are projected into the path of the products of combustion of the burner 34 for the heating of the water within the casing during the circulation of the said water after entering the same. These ribs in addition serve to deflect or retard the products of combustion throughout the path thereof to the chimney or flue.

10 The lower free end of the partition 38 within the center leg 36 is fluted or perforated at 45 so as to not obstruct the free passage of the water from the space 40 into the space 41, whereby the water will flow 15 downwardly from the spider 29 on the inner side of the partition 38, and thence upwardly on the outer side thereof within the leg 36, and finally the said water will be discharged 20 into the tube 35 for its delivery to the house system.

The central chimney or flue nipple 11 of the casing has fitted thereon a flanged hood ring 46 which is located directly above the apertures 12 in the said nipple, and forms 25 a guard to retard the inrush of air through the apertures 12 into the dome or crown of the casing.

In the operation of the heater, the water entering the water ring and casing through 30 the nipple 26 is cold, and the same is caused to pass upwardly through the water jacket between the casing 5 and the partition 23 so that the outer wall of the casing is maintained cool. The water, after rising in the 35 space 18 flows downwardly between the partitions 23 and 24 from the upper end of the casing to the lower end thereof, and thence upwardly between the partition 24 and the lining 17, whence it enters the connections 40 27 where it is distributed downwardly through the tubes 31 into the legs 30. The water rises within the legs without the tubes 31 for entrance into the spider 29, whence the same flows downwardly in the space 40 45 between the tube 35 and partition 38, and finally rises within the central leg 36 for its discharge through the nipples 42 into the tube 35 where it is delivered therefrom to the house system for consumption. During 50 the circulation of the water within the casing of the heater the same is primarily preheated in the casing, thence heated to a higher degree in the legs, and finally heated to the temperature desired prior to 55 its delivery to the house system, and by reason of the novel form of construction of the casing the use of a heating coil is obviated. Furthermore, the condensation of atmospheric water on the metal parts within the 60 casing and the lining thereof is practically eliminated, and the circulating water within the said casing is heated by the heat radiated and lost through the casing of the heaters of this type as ordinarily constructed. It is

of course to be understood that if found desirable a single water leg may be employed should the occasion require, and this is contemplated within the bounds of the invention.

It is of course to be understood that 70 changes, variations and modifications may be made such as come properly within the scope of the appended claims without departing from the spirit of the invention or sacrificing any of its advantages. 75

From the foregoing description, taken in connection with the accompanying drawings, it is thought that the construction, and manner of operation of the device will be clearly understood, and therefore a more extended explanation has been omitted. 80

What is claimed is:—

1. In a water heater, a casing, a wall spaced from and interiorly of said casing to form a water jacket coextensive therewith, inwardly directed hollow annular ribs formed from the wall at intervals thereof, water rings communicating with the jacket at its top and bottom, and co-axially arranged spaced partitions in the casing, one 90 being fixed to the upper ring and the other fixed to the lower ring to provide an uninterrupted circuitous water course in the jacket leading from one of the rings. 85

2. In a water heater, a casing, a wall 95 spaced from and interiorly of said casing to form a water jacket coextensive therewith, inwardly directed hollow annular ribs formed from the wall at intervals thereof, water rings communicating with the jacket 100 at its top and bottom, coaxially arranged spaced partitions in the casing, one being fixed to the upper ring and the other fixed to the lower ring to provide an uninterrupted circuitous water course in the casing leading from one of the rings, and a water leg 105 interiorly of the casing and disposed directly in the path of the heat from a heat generator and having communication with the jacket at a remote point of the initial 110 flow of water from one of the said rings.

3. In a water heater, a casing, a wall spaced from and interiorly of said casing to form a water jacket coextensive therewith, inwardly directed hollow annular ribs 115 formed from the wall at intervals thereof, water rings communicating with the jacket at its top and bottom, co-axially arranged spaced partitions in the casing, one being fixed to the upper ring and the other fixed 120 to the lower ring to provide an uninterrupted circuitous water course in the casing leading from one of the rings, a water leg interiorly of the casing and disposed directly in the path of the heat from a heat 125 generator and having communication with the jacket at a remote point of the initial flow of water from one of the said rings,

and a bank of hollow water legs within the body directly in the path of a heat generator and having means for causing water to be delivered from the jacket and to reversely flow in co-axially arranged columns in said legs.

In testimony whereof I affix my signature in presence of two witnesses.

JONATHAN P. SMYTHE.
